A. H. BALLARD

WINDOW

Filed July 24, 1923

Inventor:
A. H. Ballard.
by Emery Board Janney Company

UNITED STATES PATENT OFFICE.

ARTHUR H. BALLARD, OF BOSTON, MASSACHUSETTS.

WINDOW.

Application filed July 24, 1923. Serial No. 653,499.

To all whom it may concern:

Be it known that I, ARTHUR H. BALLARD, a citizen of the United States, and a resident of Boston, in the county of Suffolk and State 5 of Massachusetts, have invented an Improvement in Windows, of which the following description, in connection with the accompanying drawings, is a specification, like characters on the drawings representing like 10 parts.

This invention consists in improvements in windows and is herein shown as embodied in a car window, although as to certain of its features it may have application 15 to widely different uses.

The invention will be best understood by reference to the following description of one specific embodiment thereof, while its scope will be more particularly pointed in the 20 appended claims.

In the drawings,—

Fig. 1 is a sectional plan, partly broken away, showing a window sash in relation to the principal cooperating parts carried by 25 the frame;

Fig. 2 is a sectional elevation, partly broken away, taken on the line 2—2 in Fig. 1; and

Fig. 3 is a fragmentary rear elevation of 30 the window shown in Fig. 2.

Referring to the drawings and to the illustrative embodiment of the invention therein illustrated, I have shown one form of the invention embodied in a railroad car 35 window having a sash composed of the upright sash members 5 and the horizontal upper and lower connecting sash members 7.

The sash may be equipped with a single sheet or pane of window glass, but herein it 40 is furnished with two or more panes 9 which are permanently set in the sash, rendering the intermediate space as air tight as ordinary processes of construction permit, and providing a substantial, hermetically sealed, 45 air insulation space, while leaving but two surfaces to be washed.

The window construction herein disclosed further comprises the frame 11 presenting vertical channels or runways in which the 50 sash is freely slideable, the width of the runways for their entire length being substantially greater than the thickness of the sash, and the sash also preferably fitting the frame loosely at its edges so as to eliminate 55 any substantial friction in the movement of the sash and to permit the latter to be freely

raised or lowered without friction, as hereafter described.

To provide an efficient weatherproof joint between the sash and the frame which is 60 adapted to exclude moisture, dust and cold, while leaving the sash in such a condition as to be freely raised or lowered, the frame outside the sash is provided with seal-forming parts which extend around the outside 65 of the sash and comprise a weather strip lining 13 presenting to a cooperating part on the outside of the window sash a seal-forming seat 15. The latter may be constructed in various ways and of various materials, 70 such as felt, cloth, copper or other soft metal, but herein it consists of a strip of rubber or other resilient material cooperating with a projecting seating member or strip 17 on the opposing surface of the sash, the seating member herein comprising a metallic strip having a raised edge adapted to be pressed into the rubber or other seal-forming seat 15 and form therewith at the two 75 sides and top and bottom an efficient weatherproof joint.

It will be seen that the oversized runways permit the sash to have an appreciable movement of translation laterally or perpendicularly to the plane of the sash. To 80 seal the joint when the window sash is lowered, means are preferably provided to force the sash toward the seal-forming seat and embed the seating member 17 in the resilient strip so that the entire surrounding 85 weatherproof joint is closed. Various means may be employed for this purpose, but herein I have illustrated a plurality of cam devices 19 eccentrically pivoted in recesses in the frame 11 at each side thereof and adapted 90 each to bear with its peripheral edge against the upright sash members. Any means may be utilized to turn the cam members and thereby avail of their eccentric mounting to engage the periphery thereof 95 with the sash and force the latter outwardly to its weatherproof seat. Herein the periphery of each of the cam members is provided with radial holes 21, which, being accessible through slots 23 in the frame members, may be engaged by a suitable tool and the cams thereby turned either to apply pressure to the sash to force the latter to its seat or to withdraw pressure therefrom.

When the cams are turned to free the sash 100 from their sealing parts, the sash is preferably acted upon by devices which move the

seating member on the sash from the resilient frame seat, so that the window sash may be readily raised in its wide runways without substantial friction. For that purpose I have herein shown for illustrative purposes bearing members at each side of the frame comprising each a resiliently mounted upright bearing strip or plate 25 mounted in a recess of the frame and pre-mounted in a recess of the frame and presenting its inner, flat face to the outer face of each of the upright sash members 5. This bearing plate is provided with side flanges 27 and is engaged at intervals by limiting pins 29 which pass through the plate flanges 27 and permit a limited movement only of the plate toward and away from the sash. The plate is yieldingly pressed toward the sash by any suitable means, as, for example, a plurality of coiled compression springs 31, which are located in recesses in the frame arranged at intervals and adapted to press the plate outwardly toward the window sash. When the sash is forced laterally against its weatherproof joint, the two sides of the sash press the bearing plates back, compressing the springs 31. When it is desired to raise or lower the window the cams are turned to release the sash from the weatherproof seat and the compression springs, acting through the bearing plates, force the seating member 17 on the sash out of contact with the resilient strip 15. This leaves the sash free to be raised without friction. While the sash is being raised, the rails 25 also serve to guide the sash and prevent undue lost motion. The limiting pins 29 preferably limit the movement of the plate so that when the cams have been turned to entirely free the sash, the latter has a slight lateral play, the plate not quite touching the inner face of the sash, although, if desired, the parts may be so arranged as to permit the guide rail to press lightly against the sash. This leaves the sash free to be raised or lowered in the laterally oversized runways without any substantial opposing friction.

When the sash is raised it may be held either partly or fully raised by being pressed against the seal-forming parts, this being accomplished by turning the cams 19, or, if desired, additional window clamping devices (not shown) may be employed.

To permit the sash to be thus clamped in any partly or fully raised position, the upright seal-forming seating strips 13 and 15 are extended in the sash framing to whatever height as may be necessary to present a seating surface 15 to each projection 17 on the sash when the latter is raised, and the cams 19 are so located to present one or more sets of cams to be utilized to clamp the sash to its seat in either the closed, the partly raised or fully raised position.

The illustrated form of window is herein shown equipped with a roller shade or cur-

tain 33 of any suitable type, the same being mounted to slide for guidance in grooves 35 formed in the upright strips 37, the latter secured to the frame on the inside of the shade.

It will be seen that through the use of double panes giving the intermediate insulation space, combined with the seal-forming parts and wide runways, there is provided a window having a single sash only, capable of being raised or lowered without friction, and adapted when closed to be forced to a weatherproof seat, presenting through the seal-forming parts and the aforesaid air insulation space a structure which has a weather resistance equal to that of the double windows customarily employed.

While I have herein shown for the purposes of illustration one specific embodiment of the invention, it is to be understood that the same is not limited to the form and relative arrangement of parts, or the mechanical details thereof or the specific application herein made of the same, but that extensive deviations from the illustrated embodiment of the invention may be made without departing from the spirit thereof.

Claims:

1. A window having a sash provided with a plurality of panes permanently set therein to provide between them an insulating space, a frame presenting over-sized guideways in which said sash is freely slidable permitting said sash to have a substantial, lateral movement, seal-forming parts between the frame and the outside of the sash and extending around the latter when the sash is closed, the same comprising a seat of yieldable material and a cooperating projecting seating strip carried one by the frame and the other by the sash, cam devices mounted in the frame on the opposite side of the sash and adapted to be moved to engage the sash and force it laterally to its yieldable seat, resilient means to move the sash oppositely when the cam pressure is withdrawn and thereby free the sash from engagement with said seat and permit it to be raised and lowered in its over-sized guideways without substantial friction, said means comprising resiliently mounted bearing plates adapted one to engage each outer upright face of the sash, springs to force the plates toward the sash, and devices to limit the movement of said plates toward the sash.

2. A window having a sash adapted to be raised from or lowered to a closed position, a frame having guideways in which the sash is freely slidable and permitting a substantial lateral in and out movement of the sash, said guideways presenting fixed guiding walls to the edges and inner walls of the sash, a weatherproof joint comprising seal-forming parts on the sash extending entirely around the outside of the

same and cooperating parts on the frame adapted to register with the seal-forming parts of the sash when the latter is lowered and closed, devices to force the sash outwardly when the sash is lowered to close the joint, devices comprising flat bearing members adapted to engage each outer side wall only of the sash, resilient means tending to move said bearing members toward the sash

10 and carry the sash inwardly when the forcing pressure is withdrawn, and limiting members to limit the inward movement of said bearing members when the sash is relieved of the pressure while being raised and lowered.

3. A window having a sash adapted to be raised from or lowered to a closed position, a frame presenting runways having fixed guiding walls in which said sash is freely 20 slideable, the latter being permitted a substantial lateral in and out movement in said frame, a weatherproof joint comprising a yieldable seat and cooperating seating member, one carried by and extending entirely 25 around the sash and the other carried by the frame, said seat and seating member being adapted to register when the sash is lowered and closed, devices associated with the sash and the frame for forcing the sash to move, 30 when closed, to close the joint, movable bearing members engaging each outer side wall of the sash, the inner side walls thereof being adapted to engage with fixed walls of the runways, and resilient means tending to 35 move said bearing members toward the sash and carry the latter inwardly when the forcing pressure is withdrawn.

4. A window having a sash adapted to be raised from or lowered to a closed position, a frame having runways with fixed guiding walls in which the sash is freely slideable and in which it is permitted a substantial in and out movement, seal-forming parts between the sash and the frame and extending 45 entirely around the sash when the latter is lowered and closed, devices for forcing the sash laterally to close the joint at said seal-forming parts, bearing members adapted to engage each outer side wall of the sash, the inner side walls thereof being adapted to 50 engage with fixed guide walls of the runways, and means tending to move said bearing members toward the sash and carry the latter inwardly when the forcing pressure is withdrawn.

5. A window having a sash, a frame presenting runways in which said sash is freely slideable, the sash being permitted a substantial lateral movement in said frame, seal-forming parts between the sash and the frame and extending around the sash when the same is closed, devices for forcing the sash laterally to close the joint at said seal-forming parts when the sash is closed, and 60 devices comprising bearing members coop-

eratively related to the outer side walls only of the sash and provided with resilient means acting normally to move the sash laterally and inwardly.

6. A window having a sash, a frame presenting runways in which said sash is freely slideable, the sash being permitted a substantial lateral movement in said frame, seal-forming parts between the sash and the frame and extending around the sash when the latter is closed, devices for forcing the sash laterally to close the joint at said seal-forming parts when the sash is closed, devices comprising flat bearing members 70 cooperatively related to the outer side walls of the sash and provided with resilient means acting normally to move the sash laterally and inwardly, the inner side walls of the sash being engageable with fixed walls of said runways, and limiting devices engaging 75 each of said bearing members to limit the inward movement thereof.

7. A window having a sash, a frame presenting oversized guideways in which the sash may be raised and lowered without substantial friction and in which it may be permitted a substantial lateral in and out movement in either a raised or lowered position, seal-forming parts between the frame and the sash, a flat bearing plate mounted in the 90 guideway at each side of the sash to engage the outer side wall thereof, said plate being spring-pressed toward the sash and having means to limit its inward movement, said guideways presenting fixed guiding walls to 95 the inner walls of the sash, and a plurality of devices arranged in the frame at each side of the sash and adapted to force the latter as a whole toward and against said bearing plates and to close the joint at the seal-forming parts when the sash is closed.

8. A window having a sash adapted to be raised or lowered and provided with a plurality of panes set therein to provide between them an insulating space, a frame having guideways in which the sash is freely slideable and in which it is permitted a substantial lateral in and out movement, seal-forming parts between the sash and the frame and extending around the sash when the latter is closed, devices to force the sash to move, when closed, to close the joint at the seal-forming parts, and bearing devices 100 adapted to engage each outer side wall of the sash and acting normally to force the

105 sash laterally to open the joint, the inner side walls of the sash being subject to engagement with fixed walls of the guideways, said first mentioned forcing devices 110 co-acting with the frame to hold the sash in an elevated position when the latter is raised and opened.

In testimony whereof, I have signed my name to this specification.

ARTHUR H. BALLARD.
